UNITED STATES PATENT OFFICE.

STANLEY DUSAK, OF SEANOR, PENNSYLVANIA.

TELEPHONE-RECEIVER HOLDER.

1,092,637.

Specification of Letters Patent.

Patented Apr. 7, 1914.

Application filed May 25, 1912. Serial No. 699,699.

To all whom it may concern:

Be it known that I, STANLEY DUSAK, a subject of the Emperor of Austria-Hungary, residing at Seanor, in the county of Somers 5 set and State of Pennsylvania, have invented certain new and useful Improvements in Telephone-Receiver Holders, of which the following is a specification, reference being had therein to the accompanying drawing.

10 This invention relates to a receiver holder for telephones, and the primary object of my invention is to provide an adjustable holder for a receiver that will eliminate the necessity of holding the receiver in the hand 15 when conversing over a telephone, thereby allowing the hands to be used for other purposes.

Another object of this invention is to provide a receiver holder that can be advantageously used in connection with a wall telephone, the holder being constructed whereby it can be easily and quickly adjusted to correctly position the receiver thereof at a person's ear.

20 25 A further object of this invention is to provide an adjustable receiver holder consisting of comparatively few parts that are inexpensive to manufacture, durable and highly efficient for the purposes for which they are intended.

With the above and other objects in view, the invention resides in a novel construction, combination and arrangement of parts to be hereinafter specifically described and then 25 claimed.

Reference will now be had to the drawing, wherein:—

Figure 1 is a front elevation of a telephone provided with the receiver holder. Fig. 2 is 40 a plan of the same, and Fig. 3 is a perspective view of a portion of a pivoted arm forming part of the holder.

The reference numeral 1 denotes a wall telephone having a switch box 3 that has the ordinary receiver hook or arm 2. Suitably secured to the side of the box 3 is a bracket 4 that has the outer ends thereof bifurcated to provide apertured lugs 5 and pivotally mounted between said lugs by a pin 6 is the inner apertured end of a pivoted arm 7, said arm having the outer end thereof provided with a head 8. The head 8 is slotted, as at 9, to provide apertured lugs 10.

55 The reference character 12 indicates links of a series of links and the inner link of

said series of links is pivotally mounted upon a pin 11, which extends through the lugs 10.

The reference character 14 denotes links 60 of a series of sets of links, and the inner set thereof, which is indicated by the reference character 13, is pivotally mounted upon the pin 11. The outer link of said series of links is indicated by the reference character 12^a 65 and the outer set of said series of sets is indicated by the reference character 14^a. The link 12^a and the set 14^a are pivotally connected, by the pin 15^a, to a clamping member 15. The links 12 of the series are pivotally 70 connected together as at 12^b and the sets of links are pivotally connected together as at 14^b.

75 Detachably connected to the member 15 by a bolt 16 and a nut 17 is a clamping member 18 that co-operates with the member 15 in holding a receiver 19. For ornamentation purposes the members 15 and 18 are shaped similar to the hand. The receiver 19 is permanently connected to the pivoted links 14 80 through the medium of the members 15 and 18. The receiver 19 when the telephone is not in use is mounted in the hook 2, the members 15 and 18 being seated upon said hook. If it be desired to use the telephone, 85 the receiver 19 is removed from the hook 2 and the links adjusted so that the receiver 19 will be positioned against the ear of the party using the telephone. When the links are moved in closed position they are bent 90 upon themselves in such manner that the receiver 19 can be positioned in the hook 2.

95 The holder in its entirety can be made of light and durable metal finished to harmonize with the fittings of the telephone.

What I claim is:—

A telephone receiver holder comprising a bracket adapted to be fixed to a telephone and positioned parallel with respect to and projecting beyond the receiver hook of the 100 telephone, an arm pivotally connected to said bracket and having its outer end provided with a plurality of spaced lugs, a series of links pivotally connected together, a series of sets of links, said sets pivotally connected 105 together, means for pivotally connecting the inner link of said series of links and the inner set of said series of sets, to said lugs, a telephone receiver supporting member, means for pivotally connecting the outer 110 link of said series of links and the outer set of said series of sets to said supporting

member, and a clamping member for securing the telephone receiver to said supporting member, said links capable of being swung in the plane of said arm and further capable of being folded upon themselves, whereby the receiver can be mounted in said hook.

In testimony whereof I affix my signature in the presence of two witnesses.

STANLEY DUSAK.
